UNITED STATES PATENT OFFICE.

JOHN W. ROHRER, OF COLUMBUS, OHIO.

SPRING-PAWL DRIVE FOR STOKERS.

Application filed May 22, 1920. Serial No. 383,581.

To all whom it may concern:

Be it known that I, JOHN W. ROHRER, a citizen of the United States, residing at Columbus, in the county of Franklin and 5 State of Ohio, have invented new and useful Improvements in Spring-Pawl Drives for Stokers, of which the following is a specification.

This invention relates to power transmitting devices, particularly to pawl and ratchet mechanisms, and has for its object the provision of a spring-pressed pawl driven mechanism designed particularly for use in locomotive stokers, the particular feature of the invention being the provision of the compression spring device associated with each pawl whereby to urge the pawls into engagement with the ratchet in contradistinction to the well known tension spring 20 connected with adjacent pawls for the same purpose.

An important object is the provision of a device of this character which will be simple and inexpensive in manufacture, highly 25 efficient in use, durable in service, and a general improvement in the art.

With the above and other objects and advantages in view, the invention consists in the details of construction to be hereinafter 30 more fully described and claimed, and illustrated in the accompanying drawings in which

Figure 1 is a longitudinal sectional view through an elevator of a locomotive stoking apparatus, and

Figure 2 is a cross sectional view therethrough, showing my device in front elevation, one of the spring members of my device being shown in section, this view being 40 taken on the line 2—2 of Figure 1.

Referring more particularly to the drawings, the letter A designates the casing of a locomotive stoking apparatus, and B designates the conveyor thereof. C designates 45 the hollow shaft of the conveyor, D designates the shaft which carries a drive gear E and which extends through the hollow shaft C, F designates the ratchet secured upon the shaft D, and G designates a rotatable head 50 carried by the hollow shaft C. Certain other minor parts shown in Figure 1 are not described in detail as they are part of well-known and conventional stoking apparatus and are not essential to an understanding 55 of the invention.

In carrying out my invention, instead

of using the ordinary spring-pressed pawl connection between the ratchet F and head G, I make use of a plurality of pawls 10 which are pivoted upon the head G and 60 which are arranged in pairs disposed in opposite relation, as clearly shown in Figure 2. Adjacent each pawl, the head G is provided with a threaded hole 11 within which is screwed a guide member 12 including 65 a shank 13 which is threaded and which is formed with a bore 14 and which is formed with an angular head 15 having a socket 16 registering with the bore 14. Disposed within the bore 14 is a guide sleeve 70 17 which has a bore and which has a rounded end engaging within a recess of the associated pawl 10. Disposed within the bore of this sleeve 17 is a compression spring 18 which has one end bearing against the end of the 75 bore and which has its other end bearing against the end wall of the socket 16.

It will be seen that the springs 18 will urge the pawls 10 into engagement with the ratchet F. It will also be apparent that, 80 my device may be adjusted by virtue of the fact that the outer members thereof are screwed into holes in the head.

In devices of this character there is ordinarily provided a reversing mechanism including a parallel rotatable member H carrying arms I engageable with the pawls 10 whereby either pair of pawls may be moved out of engagement with the ratchet F. When one pair of pawls is out of engagement with the ratchet the head G will 85 be driven in one direction and when the other pawls are out of engagement with the ratchet the head will be driven in the reverse direction. While this mechanism is 90 described and shown as associated with a locomotive stoker it will be readily apparent that there is no reason why the mechanism cannot be associated with various devices in which it is desired to effect direct or reverse 95 drive between relatively rotatable members.

From the foregoing description and a study of the drawings it will be apparent that I have thus provided a simply constructed and yet highly efficient device 100 which will be advantageous inasmuch as it is very durable and a general improvement in the art.

Specifically considered it will be observed that my improvement includes means adapted to serve as a guide to the flexible pawl spring which will care for the alignment of

the spring and prolong the usefulness thereof; also, that my improvement permits of a pawl spring being removed and applied in case of inspection or renewal when the 5 spring breaks without taking the driving head apart. With my improvement all that is necessary when removal of the pawl spring is desired is to unscrew the guide nut 12 and pull the spring 18 and the spring 10 casing 17 radially outward through the threaded aperture 11. To apply a new spring, the said spring is disposed in the casing 17, and the said casing 17 is inserted in the bore of the guide nut 12 and into the 15 recess of the pawl. Then the nut 12 is simply turned into the threaded aperture in the head G. The practical advantage of this facility of displacement will be better appreciated when it is stated that in most 20 modern locomotives the space in which one is to work is very limited as is also the time for making repairs.

While I have shown and described the preferred embodiment of my invention, it is 25 of course to be understood that I reserve the

right to make such changes in the form, construction, and arrangement of parts as will not depart from the spirit of the invention or the scope of the subjoined claim.

Having thus described my invention, I 30 claim:

The combination of a head with a threaded radial aperture therein, a pawl hingedly connected to the head, a nut or threaded guide member occupying said threaded 35 aperture and closed at its outer end and having a bore open at its inner end, a casing movable rectilinearly in said bore of the guide member or nut and closed and rounded at its inner end and having said end arranged to exert inward pressure against the back of the pawl, and a spring removably arranged in said casing and in the guide member or nut and interposed between the outer end of the guide member or nut and 40 the inner closed end of the casing; the said spring being entirely housed in the guide member or nut and the casing.

In testimony whereof I affix my signature.
JOHN W. ROHRER.
